UNITED STATES PATENT OFFICE.

ERASTUS BÖRGER, OF KUNKLETON, PENNSYLVANIA.

RAILWAY-TIE AND BRACE.

1,066,073.

Specification of Letters Patent.

Patented July 1, 1913.

Application filed July 2, 1912. Serial No. 707,834.

To all whom it may concern:

Be it known that I, ERASTUS BÖRGER, a citizen of the United States, residing at Kunkletown, in the county of Monroe and State of Pennsylvania, have invented certain new and useful Improvements in Railway-Ties and Braces, of which the following is a specification.

This invention relates to railway ties and braces and more particularly to that class of such devices which are formed partly or wholly of metal.

It is the primary aim of the invention to provide a metallic tie and rail brace so constructed that the rails supported thereby may yield to the same degree as if supported by the ordinary wooden tie. In this respect, the invention aims to provide a more practical device of this type than those which have before been proposed, inasmuch as metallic ties and securing devices as ordinarily constructed, hold the rails so rigidly as to not only occasion considerable noise as a train passes thereover, but prevent any yielding whatsoever of the rails.

Another aim of the invention is to so construct the rail bracing members that the rail will be firmly supported against lateral displacement, although it may yield as above stated, when weight is imposed upon it.

The invention further aims to provide a metallic tie structure embodying novel means for preventing its lateral displacement in the road bed.

For a full understanding of the invention reference is to be had to the following description and accompanying drawing, in which:

Figure 1 is a perspective view of one end of a railway tie constructed in accordance with the present invention. Fig. 2 is an end elevation of the tie. Fig. 3 is a vertical longitudinal sectional view through one end thereof. Fig. 4 is a side elevation of one end of the tie arranged for use in a straight line of track.

Corresponding and like parts are referred to in the following description and indicated in all the views of the accompanying drawing by the same reference characters.

In the drawing the tie is illustrated as formed from stout sheet metal which is shaped up to form a channeled body the bottom of which is indicated by the numeral 1 and the sides by the numeral 2, the body being open at its ends.

As shown in the drawing the sides 2 occupy planes at right angles to the body 1 which is horizontal and each side is provided at its edge with a horizontal projecting flange 3 which flanges serve as supports for the rails which are mounted upon the tie. The bottom 1 of the body is formed in each end with an integral downwardly projecting flange 4 which, when the tie is disposed within the ballast of the road bed is embedded in the ballast and serves to prevent lateral displacement of the tie.

In addition to being supported by the flanges 3, the rails which are indicated in the drawings by the numeral 5 rest at their base flanges upon blocks 5' of wood, which are disposed within the channel of the tie body, one adjacent each end thereof, these blocks being of a width to fill the channel and being preferably slightly higher than the channel is deep so that their upper sides will be located in a plane slightly above the planes of the upper sides of the flanges 3.

Each of the rail braces forming a part of the present invention is constructed from a suitable heavy sheet metal blank and each includes a body which is indicated in general by the reference numeral 6 and which is preferably cut away at its lateral edges as at 7 to permit of the seating and removal of certain securing devices which will be presently described. This body 6 is formed at its upper inner end with a flange 8 which projects downwardly and is located in substantially a vertical plane and has an extension 9 which projects beneath the body 6 and is located in a plane approximately parallel to the plane occupied by the said body.

By referring to Figs. 1, 3 and 4 of the drawing, it will be observed that the brace is to be disposed with its flange 8 bearing against the side of the web of the rail, the upper edge of the flange resting directly beneath the head of the rail and the lower edge thereof resting in the angle formed between the upper face of the base flange and the web. The portion 9 of the flange 8 bears directly upon the upper face of the base flange and preferably projects at its free edge slightly beyond the edge of the said flange, as clearly shown in Figs. 3 and 4. It will be observed from an inspection of these figures that the body 6 is inclined downwardly and outwardly from the rail and it is formed with spaced parallel slits 10 which

extend inwardly from its lower outer edge. The material of the body between the slits 10 is bent to form a tongue 11 which extends downwardly and inwardly at an angle to the body 6, and bears frictionally and yieldably against the adjacent end of the block 5'. In order to secure the brace above described, in place upon the tie body and to firmly clamp the rail to the tie, there are 10 provided wedge-shaped bolts 12 which have heads 13 somewhat similar in form to the head of an ordinary railroad spike. Each of these wedge-bolts is formed with a slot 14 through which may be driven a wedge 15 for a purpose which will be presently explained. To receive the wedge-shaped bolts 12 each flange 3 of the tie body is formed adjacent to the rail base with a slot 16 and after the wedge-shaped bolts have 20 been driven through these slots 16, the wedges or keys 15 are driven into place and bear against the under side of the flange 3. The wedges 15 serve to draw the heads 13 of the bolts 12 firmly down upon the flange 25 portions 9 thereby causing these portions to firmly bind against the upper side of the base flange of the rail.

It will be observed from an inspection of Figs. 1 and 2 of the drawing that the portions of the body 6 at each side of the tongue 11 rest upon the upper sides of the flanges 3 and these said portions of the said flanges are formed with registering openings 17 and 18 respectively. One of the bolts 12 is 30 driven through each set of slots 17 and 18 so that the head of the bolt will be brought to bear firmly upon the upper side of the body 6 and the bolts are secured in place by means of wedges 15, as before described.

40 It will be observed from inspection of Figs. 3 and 4 of the drawing that the under sides of the head of the bolts are inclined and that they bear directly upon the upper side of the body 6 or the flange portion 9 thereof, as the case may be.

It will be apparent that by cutting away the edges of the body 6, as at 7, the bolts 12 which secure the flange portion 9 may be readily driven into place or removed.

50 When the tie and braces are to be used for supporting and holding the rails of a straight line of track, it is only necessary to provide but a single one of the braces on each tie for each rail, the brace being disposed at the outer side of the rail, as shown in Fig. 4 of the drawing, although when employed in connection with rails at curves it is preferable that two of the braces be provided upon each tie for each of the rails, the additional brace being disposed at the inner side of the rail as shown in the first three figures of the drawing.

Where but a single one of the braces is employed, as in Fig. 4, the bolts 12 may be 60 driven directly through slots 19 formed in

the flanges 3 and correspond in location to the slots 16 and are secured in place by the wedges 15, as previously described.

From the foregoing description of the invention it will be seen that the rails 5, while firmly held against displacement may nevertheless yield, and while they are securely held against overturning, may nevertheless yield to a slight but desired degree when subjected to lateral thrust by the wheels of a car passing over them.

70 It will also be understood that by reason of the fact that the lateral edges of the tongues 11 engage against the inner faces of the walls 2 of the channel, the bolts 12 which secure the spaced portions of the brace will be relieved of strain to a certain degree and the brace will be securely held against front to rear displacement upon the tie body.

80 Having thus described the invention, what is claimed as new is:

1. In a device of the class described, a channelled tie body having its upper edges provided with laterally extending flanges, 90 rail securing means extending through said flanges, a rail supporting sleeper block disposed within the channel of the body and disconnected from the rail, and means interposed between the side walls of the tie body for holding the sleeper block against lateral movement.

2. In a device of the class described, a channelled tie body having its upper edges provided with upwardly extending flanges, 100 a rail brace resting on said flanges, a sleeper block disposed within the channel of the body and arranged to support the rail, and means depending from the brace and interposed between the side walls for yieldably holding the sleeper block against lateral movement.

3. In a device of the class described, a channelled tie body having its upper edges provided with laterally extending flanges, a 110 rail brace resting on said flanges, a rail supporting sleeper block disposed within the channel of the body and arranged to support the rail and disconnected therefrom, and a resilient tongue depending from the brace and projecting within the channel of the body and bearing yieldably against the said sleeper block.

4. In a device of the class described, a channelled tie body having its upper edges 120 provided with laterally extending flanges, rail braces resting on said flanges and arranged to brace the opposite sides of the rail, a rail supporting sleeper block disposed within the channel of the body and disconnected from the rail, and a resilient tongue 125 depending from said braces and bearing yieldably against the opposite ends of the sleeper block.

5. In a device of the class described, a 130

channeled tie-body, the body being provided
at the upper edges of its walls with flanges,
a rail brace comprising a body having spaced
attaching portions resting upon the said
flanges and secured in place thereon, the
said body being inclined upwardly from its
said attaching portions and provided with a
flange arranged to bear against one side of
the web and the upper side of one base-flange
10 of a rail to be held, and means securing the
base-flange of the body to the flanges of the
tie-body.

6. In a device of the class described, a
channeled tie-body, the body being provided
15 at the upper edges of its walls with flanges,
a rail brace comprising a body having spaced
attaching portions resting upon the said
flanges and secured in place thereon, the said
body being inclined upwardly from its said
20 attaching portions and provided with a
flange arranged to bear against one side of
the web and the upper side of one base-
flange of a rail to be held, means securing
the base-flange of the body to the flanges of

the tie-body, a rail supporting sleeper-block 25
disposed within the channel of the body, and
a yieldable tongue projecting downwardly
from the body of the base between the at-
taching portions thereof and bearing against
the end of the said sleeper-block and yield- 30
ably holding the same against lengthwise
movement within the channel.

7. In a device of the class described, a
channeled tie-body having laterally extend-
ing flanges, a rail-brace resting on said 35
flanges, a rail supporting sleeper-block dis-
posed within the channel of the body, and
disconnected from the body, and a yieldable
tongue projecting downwardly and inwardly
at an angle from the brace and into the 40
channel of the tie-body and bearing against
the end of the sleeper-block.

In testimony whereof I affix my signature
in presence of two witnesses.
